STROPPING DEVICE FOR RAZOR BLADES
AND THE LIKE

Nils David Nilsson, Huddinge, Sweden

Application September 21, 1949, Serial No. 116,993
In Sweden September 24, 1947

6 Claims. (Cl. 51—153)

1

The present invention refers to such stropping devices for razor blades and the like which comprise a holder having swingably arranged therein a retaining contrivance or clip for the razor blade and provided with rollers, between which a strop is intended to be introduced. The object of the invention is to provide an efficient, simple and inexpensive stropping device and razor blade holder of this type, which occupies a small space only. A further object is to provide a razor blade holder, which may be adapted to an ordinary stropping device. These stropping devices are used so that the holder, with the strop introduced between the rollers thereof, is moved back and forth along the strop, the razor blade being sharpened thereat by the one and the other side of the edge of the blade dragging alternately along the strop. In this connection it is important that the razor blade be quickly turned or reversed from one side of the holder to the other, when the direction of movement of the holder is altered, inasmuch as the razor blade might otherwise injure the strop. In previous constructions, to ensure a rapid reversal of the razor blade, the rollers have been provided with toothed wheels, through which the movement of the rollers would be transmitted to the clip carrying the razor blade. These constructions are comparatively complicated and not always satisfactory in their function, because the friction in the teeth is frequently so great that the rollers, even in the proximity of the extreme positions, will slide along the strop without rolling thereon, so that the desired reversal of the clip and the razor blade is not obtained. A still further object of the present invention is to avoid this drawback and provide for a satisfactory reversal of the clip without resorting to toothed wheels.

The above objects are obtained by the structure illustrated by way of example in the accompanying drawing, in which Fig. 1 is a plan view of the holder when arranged on a strop, and Fig. 2 shows a corresponding elevation. Fig. 3 shows the holder in a projection at right angles to Fig. 2. Fig. 4 shows a modification in the same manner of disclosure as Fig. 3, and Fig. 5 is an edgewise view of the clip.

In the embodiment shown, the holder consists of a U-shaped yoke 1, the shanks 2, 3 of which form the side pieces in which the rollers 4, 5, 6 are mounted. The rollers are provided with end journals mounted at each end in one and the same guide taking the form of a slot 7. Preferably, the guides are straight, whereby the rollers take an aligned position. The strop 8 is intro-

duced between the rollers 4 and 5. The roller 6 carries the carrier or clip, in which the razor blade is retained. This clip may consist of a plate 10 secured to the roller 6 in a non-rotary manner and provided with pins 11 engaging apertures in the razor blade 9. The plate may have arranged thereon a cap member 12 connected with the plate at one end thereof by means of a hinge 13 so as to permit of being swung inwardly onto the razor blade placed on the plate, in which position the cap member is locked, for instance with the aid of a resilient lip or clasp 14 at the other end of the cap member. The cap member 12 preferably also has apertures provided therein in register with the pins 11.

The yoke 1 may have a block 15 or the like fitted into the same, which block may be formed with concave side surfaces offering a suitable finger grip. Arranged between the upper side of the block 15 and the roller 4 is a spring 16, preferably taking the form of a curved leaf spring, which engages with its end portions into the slots 7 in the side pieces 2, 3, where it abuts against the end journals of the roller 4. If desired, this spring 16 may be placed with the concave side thereof turned upwardly (Fig. 4). This spring presses the roller 4 upwardly against the strop 8 and also causes a resilient frictional engagement between the strop and the roller 5 as well as between the rollers 5 and 6. Roller 5 which is arranged for cooperation with the strop and which is in engagement with the roller 6 carrying the clip is provided with irregularities on its surface of engagement, said surface being preferably knurled to improve the engagement. As it is in contact with abrasive applied to the strop, it is subjected to a certain wear and should consequently consist of a relatively resistive material, such as steel.

In order that an ordinary strop, which is generally provided straps or other suspending and retaining means at the ends thereof, shall permit of being readily introduced into its place in the holder, the shanks of the yoke 1 are preferably resilient, so that the rollers 5 and 6 can be removed by moving the shanks apart, the roller journals being then pulled out of the slits 7. The strop 8 may then be easily introduced into the yoke 1 and the rollers 5 and 6 inserted anew.

The mode of operation of the device described is broadly as follows:

In the position shown in the drawing, the strop 8 is introduced into its place between the rollers 4 and 5, and the holder is taken to be in its left

extreme position on the strop with one edge of the razor blade resting on the strop. If the holder is now pulled toward the right, the roller 5, against which the strop 8 is pressed by the roller 4 and the spring 16, will be turned in a clockwise direction, the roller 6 with the clip 10 being thus swung in the opposite direction, i. e. from the right to the left, so that the side of the razor blade edge, which was previously turned upwardly, will be swung down toward the strop, until it stops against the latter. When the holder is then pulled further, the roller 6 is unable to turn, but owing to the friction between the strop and the roller 5 and between the latter and the roller 6 the roller 5 tends all the time to turn the roller 6 so that the latter keeps the edge of the razor blade pressed against the strop. In the right-hand extreme position of the holder, the rollers are turned in the opposite direction, when the direction of movement of the holder is changed, whereupon the edge of the razor blade is sharpened on its opposite side.

What I claim is:

1. A razor-stropping device comprising the combination of a holder having opposite side pieces with guides, strop engaging rollers mounted displaceably in said guides, a razor blade carrier, a further roller mounted in said guides and carrying the blade carrier, and a spring actuating the rollers to provide frictional engagement between the peripheral surfaces of adjacent rollers and between rollers and strop, whereby a rapid reversal of the blade carrier from one side of the holder to the other is obtained at reciprocation of the holder along the strop.

2. A razor-stropping device comprising the combination of a holder having opposite side pieces with slots, a swingable blade carrier, rollers mounted with their ends displaceably in said slots, one of said rollers carrying said blade carrier and another engaging the strop, the various rollers having their corresponding ends in the same slot, and a spring for providing frictional engagement between the peripheral surface of adjacent rollers and between rollers and strop to obtain a rapid reversal of the blade carrier from one side of the holder to the other at reciprocation of the holder along the strop.

3. A razor-stropping device comprising the combination of a holder having opposite side pieces with slots, a swingable blade carrier, rollers mounted with their ends displaceably in said slots, one of said rollers carrying said blade carrier and another engaging the strop, the various rollers having their corresponding ends in the same slot, and a spring in the form of a curved leaf spring having its ends engaged in the same slots as the ends of the rollers and actuating the rollers to provide for frictional engagement between the peripheral surfaces of two adjacent rollers and between rollers and the strop.

4. A razor-stropping device comprising a holder displaceable along the strop and having side

pieces with slots at opposite edges of the strop, a blade carrier swingably mounted in the holder, rollers rotatably and displaceably mounted with their ends in said slots, one of said rollers having the blade carrier secured thereto and another roller having an uneven frictional surface at its periphery in engagement with said blade carrier roller and with the strop, and spring means actuating the rollers for further pressing said rollers against the strop and toward the other rollers to provide for frictional pressure engagement between the rollers and the strop.

5. A razor-stropping device comprising a substantially U-shaped yoke having yieldable shanks with longitudinal slots, blade attaching means mounted swingably in said yoke, mutually engaging rollers having their ends mounted displaceably in said slots, one of said rollers having the blade attaching means secured thereto, a second of said rollers having a knurled peripheral surface in engagement with the first roller and with the strop, and a third of the rollers also engaging the strop, and a spring actuating the rollers to provide for engagement between the rollers and the strop to ensure a frictional contact therebetween at reciprocation of the yoke along the strop.

6. A razor-stropping device comprising a substantially U-shaped yoke having yieldable shanks with longitudinal guides, mutually engaging rollers having their ends mounted displaceably in said guides, blade attaching means comprising a plate secured to one of said rollers and a clamp member hinged to said plate, a second of said rollers having a frictional peripheral surface in engagement with the first roller and with the strop and a third of the rollers also engaging the strop, and a curved leaf spring having its ends in the same guides as the rollers and actuating the third roller to press said roller against the strop, the strop against the second roller and this latter roller against the blade carrying roller to ensure even contact pressure between the rollers and the strop and between the engaging rollers.
